UNITED STATES PATENT OFFICE.

WILLIAM J. CROSSLEY AND THOMAS RIGBY, OF MANCHESTER, ENGLAND.

GAS-PRODUCER.

SPECIFICATION forming part of Letters Patent No. 780,090, dated January 17, 1905.

Application filed April 29, 1904. Serial No. 205,597.

To all whom it may concern:

Be it known that we, WILLIAM JOHN CROSSLEY, of Crossley Brothers, Limited, Openshaw, Manchester, and THOMAS RIGBY, of 15 West Bank, Higher Openshaw, Manchester, in the county of Lancaster, England, engineers, have invented certain new and useful Improvements in Gas-Producers, of which the following is a specification.

10 Our invention has for its object the better and more economical working and greater efficiency of those gas-producers which generate gas suitable for power and heating purposes, and in order that our invention may be 15 fully understood and readily carried into effect we will describe the same with reference to the accompanying sheets of drawings.

Figure 1 is a part sectional elevation of our improved gas-producer. Fig. 2 is a sectional 20 elevation of the same.

The improved producer consists of a suitable shell, such as the metal cylinder 1, (either with or without the external superheating-jacket 2,) suitably lined with fire-bricks or 25 other refractory materials 3 and inclosed at the top. The lower portion of the producer is mounted on a circular angle-plate 4, preferably built up of and arranged in segments of a circle, which are in turn carried on small 30 piers or slabs of concrete 5 or brickwork at the floor-level. The horizontal sides of the angle-plates 4 form a support for the fire-brick lining 3, and their vertical sides dip into water contained in the spaces 6 between the 35 concrete piers and the bottom. The lower portion of the gas-producer is thereby effectually sealed, the water-lutes 7 to provide easy access for the purpose of raking ashes from the bottom.

40 In the center of the bottom portion of the producer is mounted a vertical cylinder 8, on the top of which is formed a ball-race, and the balls 9 in turn support a rotary cone fire-grate 10. The under side of the base-plate of the cone is provided with bevel-teeth 11, into which gear the teeth of a bevel-pinion 12, mounted on a shaft 13, running at right angles to the vertical center line of the producer. The shaft 13 is carried in the upper inside portion of one of two horizontal

5 pipes 14, which connect the cylinder 8 with the outside of the producer. A capstan-head 15 is preferably arranged on the end of the shaft 13 and forms a convenient means for turning the shaft 13, and so through the gearing 55 rotating the conical fire-grate 10. The cone fire-bars 16 are arranged in any suitable manner and of course rotate with the cone 10 and its base-plate, the ball-bearing 9 insuring easy rotation. The vertical cylinder 8, supporting 60 the fire-grate, is in turn either supported on the raised concrete or brickwork foundation 5 or is carried by pillars from the bed of the producer, and if the latter then the lower portion of the cylinder is sealed in the water. The 65 opposite horizontal pipes 14 are one or both of them used to transmit the superheated air or air and steam blast from the annular space between the shells 1 and 2 to the fire-grate, and suitable cleaning-doors 17 are provided 70 at their outer ends. The pipes 14 may be of any suitable shape, but are preferably of the section shown in Fig. 1 or of such other section that the descent of the burned ashes is 75 facilitated down the conical fire-grate 10 into the water-lutes 6.

The weight of the fuel mass in the present arrangement is only partly carried by the conical fire-grate 10, whereas in previous arrangements all the weight has been carried by 80 the fire-grate and made it extremely difficult, if not impossible, to move it in the case of large producers. In this case only part of the weight of the fuel is on the fire-grate 10, the remainder being carried by the bottom of the 85 producer, and as ashes are removed from the water-lutes 6 the fuel, with the help of the rotary motion of the grate, gradually and evenly descends to replace them, the diminished weight on the fire-grate 10 rendering it easily 90 rotatable by means of the gearing and from the fact that it is mounted on the ball-bearing 9.

All the air-blast or air and steam entering 95 the producer through the pipe 18 is passed in the first place down between the metal shells 1 and 2 and into the cylinder 8 through one or both of the horizontal pipes 14, and in this way the distribution of the air-blast through the perforations in the conical fire-grate 10 100

into the center of the fuel-bed is insured. The cone 10 being symmetrical and placed centrally causes the air-blast to be distributed equally over a large area, whereby gas of a 5 uniform and high calorific value is continually produced and the fuel is thoroughly consumed.

The gas generated is led away from the producer through the outlet-pipe 19. The fuel 10 is fed into the producer through a centrally-placed feeding-hopper 20 at the top of the apparatus, and ball-covered poke-holes 21 are provided at the top of the producer for inspection and poking purposes.

15 The shaft 13 may be rotated intermittently by hand or slowly and continuously by power in order to rotate the conical fire-grate intermittently or continuously, as desired.

By placing the shaft 13 in the horizontal 20 air-supply 14 and the gears 11 and 12 below the fire-grate 10 the gearing is protected by the air and steam from the fierce heat of the fire to which it would otherwise be exposed.

What we claim, and desire to secure by Letters Patent of the United States, is—

In combination in a gas-producer a vertical cylinder of but half the diameter of the producer mounted concentrically within the producer on a concrete bed or other suitable foundation, a ball-race on the top of the cylinder, a rotary conical perforated fire-grate mounted on the ball-race, horizontal pipes for the supply of air and steam to the interior of the cylinder, bevel-teeth on the base-plate of the cone, and a bevel-pinion gearing therewith and fixed on a shaft passing along one of the horizontal air-pipes and terminating outside the producer all substantially as and for the purposes herein set forth.

In witness whereof we have hereunto set our 40 hands in presence of two witnesses.

W. J. CROSSLEY.
T. RIGBY.
